IMPROVEMENT IN LAMP BURNERS.

J. J. MARCY, OF WEST MERIDEN, CONNECTICUT, ASSIGNOR TO EDWARD MILLER, OF SAME PLACE.

Letters Patent No. 60,215, dated December 4, 1866.

SPECIFICATION.

TO ALL WHOM IT MAY CONCERN:

Be it known that I, J. J. MARCY, of West Meriden, in the county of New Haven, and State of Connecticut, have invented a new Improvement in Lamp Burners; and I do hereby declare the following, when taken in connection with the accompanying drawings, and the letters of reference marked thereon, to be a full, clear, and exact description of the same, and which said drawings constitute part of this specification, and represent, in—

Figure 1, a side view.

Figure 2, a vertical central section; and in

Figures 3 and 4, the two parts of my invention.

My invention relates to an improvement in that class of burners which are constructed with a case or tube outside the wick-tube and extending above the tube, and so as to leave a space around the wick-tube, the object of the invention being to spread the flame and increase its brilliancy, and consists, first, in forming the upper end or mouth of the outer tube or case flaring or bell-shaped; and, secondly, in perforating the said outer tube near its upper end for the purpose of admitting atmospheric air directly on to the flame; and to enable others to construct my improvement I will proceed to describe the same as illustrated in the accompanying drawings.

A is the wick-tube attached to a socket, B, and provided with a wick adjuster, C, in the usual manner. D is the outer tube or case formed upon or attached to the socket, and surrounding the tube A, so as to leave a space between the two for the admission of air through openings at *a d*. The said outer case extends above the wick-tube A, and has heretofore been formed without enlargement or perforations above the point *d*. The flame from the wick rises through the tube or case D; and, in order to spread the flame, I enlarge the opening in the upper end of the case by expanding the tube into a bell shape, as seen at E, in fig. 4. This form of tube tends to expand the flame, while the contracted tube, as heretofore constructed, tends to contract the flame. This constitutes the first part of my invention. In fig. 3 the second part of my invention is represented. Through the outer case, D, and above the wick-tube A, I perforate the case D, forming openings *f*, into which a large quantity of air is drawn directly on to the flame, which tends to increase the size of the flame, and consequently its brilliancy. In figs. 1 and 2 the two of my invention are represented as combined, in which the most perfect and satisfactory results are attained.

I am aware of the patent of W. H. Smith, June 12, 1866, in which a bell-mouthed sleeve is placed over the tube, but such I do not claim.

I do not broadly claim the combination of the wick-tube A and the outer case D as of my invention; but having thus fully described my invention, what I do claim as new and useful, and desire to secure by Letters Patent, is—

1. The combination of the tube A and the case D, when the said case D is enlarged at its mouth, and the said outer case D constructed with perforations *d* near its base, substantially as and for the purpose specified.

2. The combination of the wick-tube A and case D, when the said case D is perforated near its mouth and above the wick-tube, substantially as and for the purpose specified.

J. J. MARCY.
